UNITED STATES PATENT OFFICE.

GEORGE A. WOODMAN, OF CHICAGO, ILLINOIS, ASSIGNOR OF ONE-HALF TO VINCENT J. BURRY, ONE-FOURTH TO OTTO S. FLATH, AND ONE-FOURTH TO OSBORNE E. QUINTON, ALL OF CHICAGO, ILLINOIS.

ROLLER SIDE BEARING FOR CARS.

Application filed June 2, 1923. Serial No. 642,920.

To all whom it may concern:

Be it known that I, GEORGE A. WOODMAN, a citizen of the United States, residing at Chicago, in the county of Cook and State of Illinois, have invented certain new and useful Improvements in Roller Side Bearings for Cars, of which the following is a specification.

More particularly my invention has to do with an improved side bearing for railway cars which comprises a roller housed within a suitable cage, the roller constituting anti-friction bearing means under normal conditions and its motion being controlled by the cage to prevent rectilinear motion of the roller unaccompanied by rotation thereof, so that the roller will at all times be in a position with respect to the body bolster and the truck of its car to permit it to function properly. While devices of the character described have been heretofore employed in the construction of railway cars, the means included in these devices for controlling the motion of the rollers have proved unsatisfactory in that in some instances they have shown considerable wear after a comparatively short period of service, and in other instances the motion of the roller is not effectually controlled.

The main object of my invention is to provide a side bearing for railway cars having improved means for preventing rectilinear motion of the roller unaccompanied by rotation thereof.

More specific objects of my invention are to provide a side bearing for railway cars which has improved means for effectively controlling the motion of the roller with a minimum of attendant wear to the means and to the roller, and which has means adapted to permit the roller to adjust itself with respect to the arcuate path through which the bolster of the car travels, at the same time, controlling the motion of the roller as it traverses its path.

Other objects of my invention will become apparent as the detail description progresses, reference being had to the accompanying drawings, wherein

Fig. 1 is a longitudinal section through my improved side bearing.

Fig. 2 is a plan view of my improved side bearing.

Fig. 3 is a section taken on line 3—3 of Fig. 1.

Figs. 4 and 5 are longitudinal sections of side bearings illustrating other forms which my invention may take.

Referring for the present to Figs. 1, 2, and 3, the reference character 10 designates in its entirety a lower bearing block or cage which forms a part of my improved side bearing. The cage 10 in accordance with common practice is adapted to be rigidly secured to a truck of a railway car in a position wherein a roller 11 housed within the cage may be engaged by a bolster of the car. The bolster is indicated at 12. It is the usual practice to provide each truck and its associated bolster with a pair of side bearings, the side bearings being diametrically disposed with respect to the axis about which the truck turns. Under normal conditions the rollers are spaced from the bolster, but when the car body is tilted over, the lowered end of the bolster will engage that roller which is associated with it, as illustrated in Fig. 1. This construction allows the truck to turn freely when the car is being drawn around a curve, and also prevents excessive rolling or rocking of the car body upon the center plate of the car.

The cage 10 preferably comprises a casting having integral side walls 13, end walls 14, and a bottom plate 15. Secured to the inner surface of the bottom plate 15 by a rivet 16 is a wear plate 17 upon which the roller 11 is arranged to roll.

The roller 11 comprises a body portion which is substantially cylindrical in form, but which is preferably deformed so that it tends to come to rest upon a certain line of its arcuate surface. Thus as shown in Figs. 1 and 3, the roller 11 has a plurality of recesses 20 in its ends which would in themselves tend to cause the roller to come to rest in the position wherein it is shown in these figures, in which its line of contact with the plate 17 is on its neutral axis, as the lower portion of the roller (Fig. 1) will weigh considerably more than the upper portion of the roller. And to augment the tendency of the roller to assume the position wherein it is shown in Fig. 1, I prefer to give it a somewhat egg-shaped transverse cross section. A plurality of lugs 21 pro-

jecting from the ends of the roller also add weight to the lower portion of the roller and tend to make it assume the position as shown in Fig. 1, the position being substantially midway between the end walls 14 of the cage 10.

As shown in Figs. 1 and 3, a frustro-conical head at the inner end of the rivet 16 forms a tooth 18 which engages a recess 19 formed in the roller 11 on its neutral axis, the recess 19 being formed substantially midway between the ends of the roller 11, and the tooth 18 being disposed substantially midway between the end walls 14 of the cage 10. The frustro-conical tooth 18 may be said to mesh with the roller as it permits the roller to roll toward either one of the end walls 14, but prevents rectilinear motion of the roller unaccompanied by rotation thereof. Thus when the truck which carries the side bearing turns on its axis and the roller 11 is engaged by the bolster 12, the roller will be displaced with respect to the frustro-conical tooth 18 and will approach one or the other of the end walls 14. For ordinary conditions met upon the track it will not be necessary for the roller 11 to come into close proximity with either of the end walls 14 of the cage, but when abnormal conditions are met the roller will be displaced in one direction until a lug 21 at each end of the roller comes into engagement with one of a plurality of stops 22, which are formed integrally with the cage 10. The stops 22 lie adjacent the ends of the roller and in the path of the aforesaid lugs 21. It will be noted that the stops 22 are equidistantly spaced from the tooth 18 and are so arranged that they prevent the roller 11 from rolling into positions wherein the tooth 18 would be entirely disengaged from the recess 19 formed in the roller, but when an unusually sharp curve is encountered in the track, the roller will be brought into a position wherein a pair of its lugs 21 will abut the stops 22 at one end of the cage 10. The stops 22 and the end walls of the cage will then prevent further displacement of the roller, and further angular displacement of the truck with respect to the bolster will be accompanied by a sliding engagement between the bolster and the roller. Of course, as the truck returns to its normal position with respect to the bolster, the roller will be moved toward its normal position which is substantially midway between the end walls 14 of the cage. But in any event, when the car leaves the curve in the tracks and the car body tends to assume its normal position with respect to the trucks, the bolster will assume its normal position wherein it is spaced from the rollers 11. The rollers 11 will then roll to their normal positions because of their lowered centers of gravity, described above. It is apparent that the

stops 22 and the tooth 18 co-operate to prevent rectilinear motion of the roller 11 unaccompanied by rotation thereof. It is also apparent that as all transverse sections of the roller 11 are substantially identical, the roller will seek to move in a straight path. But as the bolster 12 may be said to traverse an arcuate path with respect to the path of the roller, it will be readily understood that the roller may adjust itself to follow a path which lies intermediate its normal path and the arcuate path of the bolster. This is advantageous in that the roller will seek to follow the path wherein a minimum of wear to the bearing surfaces is occasioned. Of course, the ability of the roller to adjust itself to the particular conditions obtaining in any certain installation flows from the novel means which I employ to control the motion of the roller. Thus the use of a single frustro-conical tooth permits the inner end of the roller to lag behind its outer end when the bolster seeks to drive the outer end of the roller ahead of its inner end. Another advantage of this construction is that the stops 22 will at all times prevent the roller 11 from coming into positions wherein it could not easily roll back into its normal position. Therefore, very little play need be allowed between the tooth 18 and the roller 11, as there will be practically no abrading action between the roller and the tooth. This is because of the fact that the surface of the recess 19 need not and does not constantly engage the surface of the tooth 18. It is not necessary that the tooth constantly guide the roller as it moves from its normal position, the function of the tooth being to prevent rectilinear motion of the roller unaccompanied by rotation thereof.

I will now describe certain means which I employ to retain the roller 11 within the cage 10.

It will be noted that the cage 10 is provided with a plurality of inwardly projecting integral walls 25 which lie above the lugs projecting from the roller. Thus there is a pair of spaced walls 25 at each side of the roller which are adapted to prevent the roller from being jolted into a position wherein it would not mesh with the tooth 18, and which also prevent withdrawal of the roller from its position within the cage without first tilting it into a position substantially like that shown by the dotted lines in Fig. 1. If the roller is tilted into a position as shown by the dotted lines in Fig. 1, the roller may be withdrawn from the cage, as the lugs at each end of the roller will slip through a passageway 26 formed between that pair of inwardly projecting walls 25 which are associated with the lugs. Of course, withdrawal of the roller from the cage necessitates removal of rivets 27 which

are driven into apertures 28 in the side walls 13. The rivets 27 are provided to prevent loss of the rollers from the cages during shipment of the bearings, and need not be withdrawn from the apertures 28 unless it becomes necessary to replace the roller 11 or to replace the wear plate 17. I prefer to make the diameters of the apertures 28 somewhat less than the diameters of the rivets 27 so that when the rivets are driven into the apertures they will remain in place until they are forcibly withdrawn from the cage. The passageways 26 are of sufficient size to permit the roller 11 to be easily withdrawn from the cage after the rivets 27 have been removed, but are not large enough to permit the roller to be jolted out of the cage when it is in service, if the rivets have been removed. It is for this purpose that I incline a portion of each wall 25 as indicated at 30. The particular construction employed permits the roller 11 to move freely through its path but insures against accidental loss of the roller.

In Fig. 4 I have shown a side bearing which illustrates another form my invention may take. This side bearing comprises a cage 10^a housing a roller 11^a. The cage 10^a and the roller 11^a are substantially like the cage 10 and the roller 11 respectively of Figs. 1, 2, and 3, with the exceptions that the roller 11^a is provided with lugs 21^a which differ from the lugs 21 of the roller 11, and that the cage 10^a is provided with stops 22^a which differ from the stops 22 of the cage 10. The stops 22^a not only prevent shifting rectilinear motion of the roller 11^a toward its normal position within the cage 10^a, but each of the stops is provided with a shoulder 32^a against which its associated lug 21^a may rest, the lugs 21^a being provided with plane surfaces 33^a adapted to lie against the shoulders 32^a of that pair of stops 22^a which control the roller 11^a when the roller is at one or the other end of its limited path of travel. It is apparent that the shoulders 32^a aid the end walls 14^a of the cage 10^a in their task of holding the roller 11^a immovable when the truck still continues to turn after the roller has been brought into a position wherein it lies adjacent one of the end walls 14^a.

In Fig. 5 I have shown a side bearing which embodies the novel features of my invention and which resembles the side bearing illustrated in Figs. 1, 2, and 3. The side bearing shown in Fig. 5 comprises a cage 10^b housing a roller 11^b, which is adapted to roll upon a wear plate 17^b secured to the bottom wall 15^b of the cage 10^b by means of rivets 34^b. The roller 11^b is provided with lugs 21^b projecting from its ends, the lugs 21^b being identical with the lugs 21 of the roller 11 shown in Figs. 1, 2, and 3. The lugs 21^b are adapted to co-operate with

stops 22^b which are formed integrally with the cage 10^b. It is apparent that this construction is identical with the construction employed in the side bearing shown in Figs. 1, 2, and 3. But in the side bearing shown in Fig. 5, the roller 11^b is provided with a frusto-conical tooth 18^b which may be employed in place of the frusto-conical tooth 18 of the side bearing shown in Figs. 1, 2, and 3. The frusto-conical tooth 18^b is adapted to mesh with the cage 10^b, the wearing plate 17^b being provided with a recess 19^b adapted to receive the tooth 18^b. The operation and advantages of this construction are apparent.

I am aware that changes in the form, construction and arrangement of parts may be made without departing from the spirit and without sacrificing the advantages of the invention and I reserve the right to make all such changes as fairly fall within the scope of the following claims.

I claim:

1. In a side bearing for cars, the combination with a roller having lugs projecting from its ends and a recess in an arcuate surface thereof, of a cage comprising a single tooth engaging the recess in the roller, and stops adapted to engage the lugs of the roller to prevent rectilinear motion of the roller toward the tooth without accompanying rotation of the roller.

2. In a side bearing for cars, the combination with a roller having lugs projecting from its ends, of a cage comprising a single tooth meshing with the roller, stops spaced from the tooth and disposed in the path of the lugs projecting from the roller, and means for engaging the lugs to prevent disengagement of the roller from the tooth.

3. In a side bearing for cars, the combination with a roller having lugs projecting from its ends, of a cage comprising a single tooth meshing with the roller, stops spaced from the tooth and disposed in the path of the lugs projecting from the roller, and walls having surfaces disposed substantially parallel to the path of the roller and adapted to engage the lugs to limit displacement of the roller relative to the tooth.

4. In a side bearing for cars, the combination with a roller having lugs projecting from its ends, of a cage comprising spaced walls adapted to engage the lugs to prevent direct withdrawal of the roller from the cage, and separable means disposed intermediate the walls for preventing accidental loss of the roller from the cage.

5. In a side bearing for cars, two members, a cage and a roller therein, one of said members having a single tooth meshing in a recess in the other of said members, said tooth and said recess being disposed substantially centrally of said cage, lugs on the end of said roller and stops on the bottom of said

cage on either side of said tooth and said recess to engage said lugs to limit the movement of said roller.

6. A side bearing for cars, comprising two members, a cage and a roller therein, said roller being deformed so that it tends to come to rest in a certain position with its neutral axis in contact with the bottom of said cage, and a tooth on one of said members meshing in a recess in the other of said members, said tooth and said recess being disposed in the neutral axis of said roller when it is at rest in its normal position.

10 7. A side bearing for cars, comprising two members, a cage and a roller therein, said

roller being deformed so that it tends to come to rest in a certain position with its neutral axis in contact with the bottom of said cage, and a tooth on one of said members meshing in a recess in the other of said members, said tooth and said recess being disposed in the neutral axis of said roller when it is at rest in its normal position, lugs on either end of said roller and disposed at the opposite sides of said neutral axis and stops on the bottom of said cage, and adapted to engage said lugs to limit rotation of said roller.

GEORGE A. WOODMAN.
